United States Patent Office.

MANUEL J. VIEIRA, OF MENDOTA, ILLINOIS.

Letters Patent No. 67,467, dated August 6, 1867.

IMPROVED SHAMPOOING MIXTURE.

The Schedule referred to in these Letters Patent and making part of the same.

TO ALL WHOM IT MAY CONCERN:

Be it known that I, MANUEL J. VIEIRA, of Mendota, in the county of La Salle, and State of Illinois, have invented a new and useful Improvement in Liquids for Cleansing the Hair; and I do hereby declare that the following is a full, clear, and exact description of the same.

The object of this composition is to provide a liquid which may be used as a wash in shampooing the hair without resorting to the use of water to remove the shampooing liquid after it has been applied.

In compounding this preparation take seven and a half ($7\frac{1}{2}$) ounces of alcohol or cologne spirits, also seven (7) ounces of soft water. Cut six (6) drachms of castor oil with two (2) drachms of alcohol, add two (2) ounces of aqua ammonia, and shake well to incorporate the ingredients. Any perfume may be added, according to taste.

The liquid thus compounded is applied by rubbing enough into the hair to make a good lather. Then scratch the head thoroughly to clean the scalp, by which time the lather will have disappeared. Then rub with a towel until the hair is dry enough to dress.

What I claim as my invention, and desire to secure by Letters Patent, is—

A composition of a liquid for use in shampooing the hair, compounded from the ingredients substantially as set forth

In testimony whereof I have signed my name to this specification in the presence of two subscribing witnesses.

MANUEL J. VIEIRA.

Witnesses:

J. W. HODGE,

GEO. W. SNYDER.
